(57) **CLAIM**

The ornamental design for a mechanic's creeper as shown and described.

DESCRIPTION

FIG. 1 is a front, left, top perspective view of a mechanic's creeper according to my new design, wherein the mechanic's creeper is in a first position;

FIG. 2 is a rear, right, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, left, top perspective view thereof, wherein the mechanic's creeper is in a second position;

FIG. 10 is a rear, right, bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the figures depict portions of the mechanic's creeper that form no part of the claimed design.

1 Claim, 15 Drawing Sheets
